UNITED STATES PATENT OFFICE.

FRANK DESMOND SPRAGUE, OF NEWPORT, RHODE ISLAND.

AUTOMATIC ANGLE COCK.

Application filed October 22, 1921. Serial No. 509,754.

To all whom it may concern:

Be it known that I, FRANK DESMOND SPRAGUE, a citizen of the United States of America, and a resident of the city of Newport, in the county of Newport and State of Rhode Island, have invented certain new and useful Improvements in Automatic Angle Cocks, of which the following is a specification.

10 This invention relates to a brake pipe angle cock for use on railway air brake systems, its object being to provide an improved device which shall automatically maintain an open brake pipe passage so long as the hose couplings between cars are connected, irrespective of any accidental or malicious closing of the angle cock handle, and which will also operate to close said passage automatically when the cars are uncoupled, provided the operating handle has been placed in a closed position.

The angle cock at present generally used is a manually operated cone valve and is a source of potential danger. Should the handle of such an angle cock be accidentally or maliciously closed when on the road it would be impossible to apply or control the brakes to the rear of the closed cock, and the consequent loss of braking power might be the cause of serious accident. Its essential part is a ground valve-seat combination which requires periodic grinding, and when not in good condition will result in an appreciable loss of brake pipe air with a consequent excess duty imposed on the locomotive air compressor.

The angle cock described in the following specification is designed automatically to maintain the opening of the brake pipe so long as the hose couplings between cars are connected, irrespective of any movement of the angle cock handle. It takes the place of the valve in present use and is manipulated by the railroad crew in like manner. No changes in procedure will be required in making up trains or uncoupling cars. In addition to the automatic maintenance of brake pipe passage, in a large percentage of cases these valves will automatically open as soon as hose couplings are

connected even should the yardmen neglect to move the operating handle to open or running position.

Referring to the drawings:

Figure 1 is a longitudinal section showing an angle cock embodying my invention in a closed position; 55

Fig. 2 is a similar view showing the angle cock in open position;

Fig. 3 is a longitudinal section, broken away, showing two oppositely disposed angle cocks of the type illustrated in Figs. 1 and 2 and their attendant hose couplings; 60

Fig. 4 is a diagrammatic view illustrating a series of angle cocks, hose couplings, etc., as connected in a train, portions of the brake pipe being broken away; 65

Figs. 5 and 6 are longitudinal sections corresponding with Figs. 1 and 2 and illustrating a modification in the form there shown; 70

Figs. 7 and 8 are similar views illustrating a further modification in which the differential pressure area necessary to maintain the angle cock in the open or operating position against the pressure of the closing spring is secured by means of a soft-seated valve instead of by means of sylphon bellows, and 75

Fig. 9 is a cross section illustrating a ball lock for the angle cock handle, applicable for use in connection with my invention. 80

Similar reference characters indicate corresponding or equivalent parts throughout the several views of the drawings. 85

Referring to Figs. 1 and 2 the main body casting 10 of the angle cock is closed at one end with a cap 12 and at the opposite end is provided with a cap 11 for engagement with the brake pipe of the locomotive or car by means of the threaded portion 13. It is extended at one side to form a chamber 18 through which communication is made with the hose coupling between the several units of the train, a threaded portion 14 being provided for this purpose. 90

The cap 11 forms a chamber 15 and its inner portion is reduced and terminates in a valve seat 41 for cooperation with a valve 40. This valve is formed on the outer face 100

of a piston 26 which reciprocates in a liner 25 suitably mounted in the interior of the casing and preferably made of bronze. The piston divides the left hand portion of the body into two chambers 16 and 17 respectively, chamber 16 being in open communication with chamber 18 and being in communication with chamber 17 through a small equalizing port 28. This piston is extended to form a spring cage sleeve 29 which has a sliding fit in an anchorage collar 36, and is designed to retain the seating spring 30 which is thus mounted between the piston 26 and the cap 12. This spring is of sufficient strength to hold valve 40 closed against any working air pressure that may be present in chamber 15. The anchorage collar 36 provides for a chamber 19 to the right of the body which is at all times at atmospheric pressure. A sylphon bellows of smaller outside diameter than the piston is soldered to the right hand face of the piston and to the left hand face of the anchorage collar thus preventing leakage between the anchorage collar and the piston. Leakage between the anchorage collar and its mounting in the body is prevented by a gasket 37 put under pressure by the screw retaining ring 38. The interior of the sylphon is at atmospheric pressure, being in communication with the chamber 19 along the sliding fit between the collar 36 and the piston. The bearing of this upon the operation of the device will be further explained.

The extended portion 29 of the piston 26 is provided with a collar 50 for engagement with an off-centered cam 51 which latter is operatively attached to a handle 55 for manual operation of the angle cock. A ninety degree movement of the handle from the position of Fig. 1 to that of Fig. 2 results as disclosed in the latter figure in a movement of the piston 26 to the right against the pressure of spring 30 to open valve 40 and thus establish unobstructed communication between chambers 15 and 16. The handle 55 is designed to be self-locking on each extreme of its 90 degree movement due to suitable ears 56 registering with two stop lugs which are not shown in the drawing.

In order to insure automatic opening of this valve should the handle be neglected, a small one way air passage 45 connects chambers 15 and 16 via the ball check valve 46 and 47. The major air passage from chamber 15 to chamber 16 is in Fig. 1 indicated blocked by means of valve 40 registering with its seat 41.

Operation—normal procedure.

As before stated, Fig. 1 indicates the angle cock in closed position. For the purpose of this description this cock will be

considered as in the rear of the locomotive tender. The pressure air will be contained in a tender brake pipe chamber 15. Prior to coupling up a minute portion of this air is constantly discharged to atmosphere via the bleed hole 45, the ball check valve, and chambers 16 and 18. This is a necessary waste but is microscopic in quantity. It should be noted that as the bleed hole 45 does not discharge directly to the atmosphere, the chances of freezing at this point are materially reduced.

The major passage via valve 40 is maintained closed by the pressure of compression spring 30, which is sufficiently powerful to resist the air thrust on the piston valve when closed.

When the cars are coupled the yardman moves handle 55 ninety degrees from its closed position and such movement will cause cam 51 to engage with cam ring 50 and lift valve 40 clear of its seat 41. The main air passage from the tender brake pipe to the hose couplings is thus established and will be mechanically maintained irrespective of any variation in brake pipe pressure as long as cam handle 55 is left in running position.

Self opening operation.

Should the yardman forget to operate the valve handles after the hose couplings are connected the valve will open automatically, due to the following sequential pneumatic process.

Air will seep through bleed hole 45, pass by ball check 46, 47, and will tend to establish a pressure in chamber 16, chamber 18, hose connections, and chambers 18 and 16 of the No. 1 car valve, which is reversed in position. Note Figs. 3 and 4. This air will gradually increase in pressure, due to further progress to the rear of No. 1 car valve being blocked by the ball check at that point. This pressure will equalize between chambers 16 and 17 via equalizing port 28, but while the unit air pressure is the same on both sides of the piston the summation in chamber 16 will be greater than that on the right hand due to the differential area established by the sylphon bellows. The interior of these bellows is, as above stated, at all times at atmospheric pressure. This differential area prior to opening the angle cocks is equal to the net effective area of the sylphon (measured to its solder rim), minus the area of the valve 40, for all car valves on the pressure or locomotive side of the train units. The area of the valve 40 may be disregarded in car valves on the opposite side of the units.

As thus indicated, irrespective of the yardmen neglecting to move handle 55 to running position, the valve will automatically open when the unit pressure generated

by air leakage to chamber 16, multiplied by the above mentioned differential area equals the over balance of spring 30 against the total pressure on valve 40.

5 Once open the net differential area for car valves on the pressure side is increased by the cross section of the valve 40 so that this differential amounts to the net area of the sylphon. The spring is thus opposed to 10 an increased over balance air pressure.

As the car brake pipe is initially at atmospheric pressure the car valve will lag behind that on the locomotive, due to the absence of the air thrust on the valve 40. If it 15 is left entirely to leakage, the pressure built up by the same must therefore be greater than that which sufficed to open the locomotive valve.

Prior to the leakage pressure in the hose 20 couplings reaching the required amount, the locomotive valve has gone to open position automatically. In consequence full brake pipe pressure will fill the hose couplings and cause a quick opening of the front car valve.

25 This sequential operation of oppositely placed valves is of paramount importance, as all the leakage air by check valves 46, 47, is called to do is to build up the locomotive valve opening pressure in the small capacity 30 represented by the hose connections. The main brake pipe on each car is charged from full brake pipe pressure when the front valve on said car opens.

As cam 51 is single acting, the accidental 35 or malicious placing of the cam handle in the off or closed position would have no effect as long as the valve has originally been opened, as the piston would still continue to remain in running position through the differential pressure established by the sylphon 40 so long as the brake pipe pressure is not reduced below a definite point. This point is considerably lower than that reached by full service reduction from any brake pipe pressure.

When cars are uncoupled the formal procedure for the yardman to follow would be to move the angle cock handles to closed position and then disconnect the flexible hose.

50 The breaking of the hose joint will cause pressure in chambers 16 and 18 instantly to drop to atmosphere, as the discharge capacity of these chambers and the hose is sufficiently great to care for any air being supplied through valve 40.

Piston valve 40 will now automatically 55 close to prevent any further discharge, except the minor amount coming through the check valve, due to pressure of spring 30, supplemented by air momentarily trapped in chamber 17.

Should the train part on the road due to defective coupling, this automatic action of the piston valve will not occur if the cam 51 is in the normal running position (Fig. 2).

Consequently full emergency braking will result from a broken coupling as at present.

Emergency braking will likewise occur in a break-in-two on both sections of the train even if intermediate handles are in 70 closed position. This has been ascertained by actual testing and is probably due to the capacity of the brake pipe and the fluid friction both of which are absent when the hose coupling is parted between two closed 75 brake cocks. The time required in exhausting the brake pipe apparently results in the maintaining of sufficient pressure on the valve face of the piston 26 to maintain the valve in open position until the emergency 80 braking has been effected.

The figures now under discussion while 85 purely illustrative and not intended to limit the invention are drawn to scale from tested apparatus and may if desired be used as a guide in the proportioning of parts.

From the above it may be seen that the principal value of the handle is to prevent undesired closing of the valve should the 90 train part on the road.

The modification illustrated in Figs. 5 and 6 follows so closely the structure of Figs. 1 and 2 that it is believed its construction and mode of operation will be readily understood without repetition. The valve 95 has been replaced by a soft seated self-aligning type, and in order to prevent chattering of this valve the feed port 45 has been transposed to the discharge side. In order to protect the piston ring and cylinder walls 100 from abrasive action of sand and grit that may be discharged by the brake pipe during emergency applications, and also to facilitate the quick closing of valve 40 when the hose is parted in uncoupling with the cam 105 51 in closed position by relieving the piston 26 from the kinetic blow of the moving air, baffle plate 80 has been introduced. On the parting of the hose coupling static pressure on the left face of piston 26 is reduced, 110 as in the earlier forms, via passage 81, but the kinetic energy of the air rushing through the main valve 40 is partially absorbed by the baffle plate 80. The equalizing port 28 illustrated in Figs. 1 and 2 has been eliminated but pressure air will be built up in the chamber to the right of the piston 26 by leakage past the piston.

Various minor detailed mechanical changes 120 are introduced, such as shortening of the sylphon bellows, introduction of the ball lock 90 (see Fig. 9) on the stem 52 of cam 51, which takes place of the locking ears 56. The ball lock 90 is of simple construction 125 and merely comprises a spring pressed ball suitably mounted in the cap 100 for engagement with an annular grooved sector on the valve stem.

It should be noted that the main body 130 casting has been somewhat simplified, and a

one-ended assembly made possible by the adoption of the flange cap 100, which is secured by means of cap screws 101 in place of the screw cap 12 as illustrated in former figures. Furthermore the cap of Figs. 1 and 2 at the opposite end of the valve containing the chamber 15 is here illustrated as integral with the body casting.

The modification illustrated in Figs. 7 and 8 it is believed likewise will be understood both as to construction and operation from the foregoing description. In both of these respects the structure follows generally that of Figs. 5 and 6, the difference being in the means by which requisite differential area on the operating piston necessary to maintain the valve in open position against a thrust of spring 30 is secured. In the construction of these figures this is accomplished by means of a soft seated valve indicated by numerals 110—111 in place of the sylphon bellows 35. In all other respects of mechanical construction the mechanisms are identical.

In this modification the pressures at the beginning of operation are slightly different. When the brake pipe valve is closed the entire space to the right of operating piston 26 is at atmospheric pressure and any leakage by ring of said piston will pass to atmosphere until valve 110—111 closes. Once this valve is closed the differential area is definitely established and is determined by the valve diameter. Any minor leakage of air due to an imperfect seat will pass to atmosphere via a leakage port 112.

The foregoing detailed description has been given for clearness of understanding, and no undue limitation should be deduced therefrom, but the appended claims should be construed as broadly as permissible in view of the prior art. The word "cars" is employed in the claims broadly to indicate the units of a train whether the same be power units or units drawn by power units.

Having thus described my invention, what I claim as new, and desire to secure by Letters Patent, is:

1. The combination with an air brake system, of an automatic valve located in and controlling the passage of air through the brake pipe, which when once opened will automatically maintain this opening so long as the hose couplings between cars are connected, and means for manually opening said valve.

2. The combination with an air brake system, of an automatic valve located in and controlling the flow of air through the brake pipe of such system, equipped with means for manually opening said valve and so designed as automatically to close upon the parting of the hose couplings following a release of the manually opening means.

3. The combination with an automatic air brake system, of an automatic angle valve normally obstructing the flow of air through the brake pipe, means for manually opening this valve, and means for insuring automatic closing of same on the parting of the hose couplings following the restoration of the manual opening means to "off" position.

4. The combination with an air brake system of a device for controlling the flow of air through the brake pipe, comprising a valve, a movable piston controlling said valve, a spring for maintaining the valve in closed position, means for subjecting the valve controlling piston to differential air pressure, and means for manually opening the valve and for maintaining the valve in an open position.

5. The combination with a piston-controlled valve substantially as described, of a spring for maintaining the valve in closed position, a flexible metallic bellows for establishing a differential pressure area upon the piston, means for manually opening said valve, and means for insuring an automatic opening of said valve upon the completion of hose connection between cars, should the manual means be neglected.

6. An automatic angle cock valve comprising a cylinder, a piston sliding therein, a valve operated by the movement of said piston and capable of controlling the flow of brake pipe air, a spring for normally maintaining the valve closed, a flexible metallic bellows for establishing a differential pressure area upon the piston, a manually operated cam and engaging ring for opening said valve, and a feed port and check valve to cause an automatic opening of the said valve upon completion of hose connections should the manual means be neglected.

7. An automatic angle cock valve, comprising a cylinder, a piston sliding therein, a valve operated by the movement of said piston and capable of controlling the flow of brake pipe air, a spring for normally maintaining the valve closed, an additional valve for establishing a differential pressure area upon the piston, a manually operated cam and an engaging ring for opening said piston operated valve, and a feed port and check valve to cause an automatic opening of the piston operated valve upon completion of hose connections should the manual means be neglected.

8. A brake pipe angle cock valve, comprising a cylindrical casting, a piston sliding therein, a valve controlling the flow of brake pipe air operated by movement of said piston, a baffle plate for partially protecting the piston from the kinetic blow of flowing brake pipe air, a spring for holding said piston operated valve in closed position, a man-

ually operated cam for opening said valve, means for locking said cam at each extreme of its movement, means for establishing a differential piston area to insure the piston operated valve remaining in open position should the manually operated cam be moved to "off" position, and means for insuring an automatic opening of the valve by accumulation of air pressure in the connecting hose as soon as the hose couplings between 10 cars are made.

Signed at New York, N. Y., this 21st day of October, 1921.

FRANK DESMOND SPRAGUE.
